UNITED STATES PATENT OFFICE.

ROBERT CHARLES MENZIES, OF GLENS FALLS, NEW YORK.

SNOW-SHOVEL.

SPECIFICATION forming part of Letters Patent No. 760,639, dated May 24, 1904.

Application filed August 27, 1903. Serial No. 170,984. (No model.)

To all whom it may concern:

Be it known that I, ROBERT CHARLES MENZIES, a citizen of the United States, residing at Glens Falls, in the county of Warren and State of New York, have invented a new and useful Snow-Shovel, of which the following is a specification.

This invention relates to shovels, and especially to that class of shovels which are usually employed for the purpose of removing snow, ice, and compacted snow from sidewalks. In the construction of shovels of this class several features are of essential importance. One point is that the blade of such shovel should be as thin as possible in order that it may be conveniently inserted below the ice or snow which it is desired to remove, especially when the snow has been compacted or pressed together by traffic. Another point is that it is desirable that such blade should not be provided with side flanges, which when used greatly limit the capacity of the shovel by causing such snow or ice as may project beyond the sides of the blade to be broken off, while the natural tenacity of said material when a flat flangeless blade is used enables a much larger shovelful to be handled. Again, it is important that the blade while thin should be possessed of the stiffness and rigidity necessary to render it successful in operation. With these various ends in view snow-shovels have heretofore been constructed in a number of different ways and from different materials. When steel blades have been used, it has been customary and, in fact, it has been found almost indispensable to provide them with side flanges, which is objectionable for the reasons above set forth. Wooden blades have been used shod or provided with cutting edges of steel or other suitable material. Such shovels have had the advantage of lightness and facility of handling; but the blades have hardly been sufficiently thin to enter below the snow or ice which is to be operated upon with the requisite readiness. Handles have been attached to the different varieties of shovel-blades in a variety of ways; but the handle in itself has always been more or less objectionable, and the method of attaching it has oftentimes involved peculiarities in the

construction of the blade which have in themselves been objectionable.

By my present invention I provide a shovel consisting of a simple flat piece of steel having no flanges or protuberances of any kind whatever. This sheet is attached to a bent wooden handle in such a manner that the sheet at its point of contact with the handle becomes bent in such a manner as to enable it to resist any strain to which it may in practice be subjected. The method of connecting the parts together is of extreme simplicity and of such a nature as to cause no objectionable protuberances to be formed.

In the accompanying drawings, Figure 1 is a plan view of a snow-shovel constructed in accordance with my invention. Fig. 2 is a side elevation of the same. Fig. 3 is a side view showing the blade prior to its attachment to the handle. Fig. 4 is a side view showing the handle detached. Fig. 5 is a longitudinal sectional view showing a modification. Fig. 6 is a sectional view taken on the line 6 6 in Fig. 2. Fig. 7 is a sectional view taken on the line 7 7 in Fig. 5. Fig. 8 is a sectional view taken on the line 8 8 in Fig. 1.

Corresponding parts in the several figures are indicated by similar numerals of reference.

The blade of my improved shovel consists of an ordinary flat sheet of steel 1 of suitable dimensions, the upper corners of which may be trimmed off, as shown at 2. This is not strictly necessary, but it improves the appearance and prevents said upper corners from catching on the garments of the user.

3 designates the handle, which may be turned from wood and the lower end or point of which is bent upward, as shown at 4. The under side of said bent end is also trimmed or beveled, as shown at 5, said bevel serving to emphasize the bend of the point or lower end of the handle.

The sheet which constitutes the blade is provided near its upper edge with perforations 6 6 and, at some distance from its lower edge with a single perforation 7.

In assembling the parts of the shovel the point of the handle is placed upon the sheet which is to constitute the blade, and a clip 8

is passed over said handle and through the perforations 6 6, nuts 9 being tightened upon the threaded arms of the clip. The handle is provided near its extreme lower end with a 5 perforation 10, and a T-bolt 11 is then inserted through said perforation and through the perforation 7 in the blade and a nut 12 fitted thereon, this necessitating the bending of the blade in order to bring the said perforations 10 into alinement. These perforations 7 and 10 should be relatively so disposed that when they come into alinement with each other the blade shall be bent closely against the bent and beveled under side of the handle.

15 If desired, the use of the fastening-nuts may be dispensed with and the ends of the clip and of the T-bolt, that project upon the under side, may be clenched or upset. In this case it is desirable to interpose washer-plates, 20 as will be seen at 15 in Figs. 5 and 7, where this modification has been illustrated.

From the foregoing description, taken in connection with the drawings thereto annexed, the operation and advantages of my invention will be readily understood. By forming the blade of sheet-steel, as herein described, I provide a device possessing great 25 strength and durability and one which to a greater degree than a flanged or a wooden 30 blade possesses the characteristics which are desirable in a tool of this class. The construction is one of extreme simplicity and inexpensiveness, and, if desired, the blades and the handles may be packed separately for ship-

ment, thereby saving much space and avoiding injury to the goods in transit. The peculiar tapering form of the lower end of the handle will present little or no obstruction to the snow or ice which is encountered by the device in practical use.

40 Other advantages will readily suggest themselves to those skilled in the art to which my invention appertains, and I desire to state that I do not limit myself to the precise structural form herein shown, but reserve the right to 45 any modifications that lie within the scope of my invention and which may be resorted to without departing from the spirit or sacrificing the utility of the same.

Having thus described my invention, I 50 claim—

A snow-shovel comprising a blade consisting of a flat sheet of steel, a handle having a bent lower end beveled on its under side, a clip connecting said handle with the blade 55 near the upper edge of the latter, and connecting means extending through perforations at the point of the handle and in the blade, said perforations being brought into alinement by bending the blade to conform to 60 the curvature of the handle.

In testimony that I claim the foregoing as my own I have hereto affixed my signature in the presence of two witnesses.

ROBERT CHARLES MENZIES.
